ASSEMBLER MECHANISM OF TYPOGRAPHICAL COMPOSING MACHINES

Arthur Staniland Hayward, Altrincham, England, assignor to Linotype and Machinery Limited, London, England, a registered company

Application February 10, 1937, Serial No. 125,023
In Great Britain February 15, 1936

20 Claims. (Cl. 199—21)

This invention relates to typographical composing machines such as those known commercially under the registered trade-mark "Linotype", and more particularly to machines embodying a plurality of superposed magazines and an assembler entrance adjustable to permit the assembling of matrices from a plurality of magazines while the magazines remain stationary.

Among the objects of the invention are to provide an improved form of key-controlled power-operated mechanism for effecting the adjustment of the assembler entrance; to provide such mechanism in the form of a self-contained unit capable of adjustment on the machine to an inoperative position wherein parts of the mechanism itself and of the machine adjacent thereto are more readily accessible; to adapt such a unit for controlling the independent adjustment of a plurality of assembler entrances arranged side by side and to facilitate the before-mentioned adjustment of mechanism thus adapted in machines having separate keyboards appropriate to the different groups of magazines served by the respective assembler entrances.

With these objects in view, the invention consists in a device for setting an adjustable assembler entrance in a typographical composing machine, comprising a power-driven member and a key controlled member adapted for frictional engagement therewith to actuate a mechanical power transmission system whereby the assembler entrance is adjusted to the desired setting.

The invention will be clearly understood from the following description of one form which it may assume (given, however, merely by way of example), and this description will be more readily followed by reference to the accompanying drawings, wherein:—

Figures 1 and 2 represent respectively in side view and rear view a mechanism according to the invention;

Fig. 3 is a side view of a portion of a typographical composing machine embodying the invention and showing the assembler entrance in one position of adjustment;

Fig. 3a is a side view similar to Fig. 3, showing the assembler entrance in another position of adjustment; and

Fig. 4 is a plan view of a portion of a typographical composing machine embodying the present improvements.

In carrying the invention into effect in one convenient manner, as shown in Figures 1 and 2 herewith, (which illustrate duplicate mechanisms according to the invention combined as one unit),

there are provided a continuously rotating roller 1, and a cam 2 eccentrically mounted in a yoke 3 which is pivoted at one end and normally held, by a trip dog 4 engaging beneath its free end, in a position in which the cam 2 is above and out of contact with the roller. The roller 1 and cam 2 are preferably of metal, the roller having a V-shaped peripheral groove and the cam a V-shaped periphery adapted to engage with the said groove, as shown in Figure 2. When the trip dog 4 is actuated, by the depression of a finger key 5, to release the yoke 3, the latter falls by gravity and the cam 2 is rotated by contact with the roller 1 thus raising the yoke 3, during which raising (the finger key 5 having been released), the dog 4 returns to position to support the yoke 3 and the cam 2 is brought to rest out of engagement with the roller 1 by a laterally projecting pin 6 thereon coming against a stop 7. This operation is similar to that of the known key-board cam mechanism, but in the present instance the yoke 3 serves to raise a push rod 8 which in turn is adapted to effect a definite angular movement of a cam 13 controlling the position of the assembler entrance through a lever 25 actuated by the cam.

In the construction shown, the push rod 8 actuates a spring-loaded rocker 9 carrying a pawl 10 engaging a ratchet wheel 11 operatively fast to the cam 13, the rocker 9 being loosely mounted on the stud or shaft 12 carrying the cam 13 and ratchet wheel 11.

The cam 13 consists of a disc 14 having a cam groove in one face within which engages a roller 15 on a stud projecting laterally from a lever 35 arm 16 connected with the assembler entrance. The disc 14 is preferably also formed with notches 17 in its periphery which are engaged by spring pawls 18, 19 to prevent over-running or rebounding of the cam, so that the latter is positively locked in successive positions corresponding to alternating high and low portions of the cam, the entrance control lever 16 thus being adjusted and locked by successive depressions of the finger key in different positions controlling different operative positions of the entrance. The release of one of the last-mentioned pawls may be effected by the depression of the control finger key (e. g. by the linkage 20, 21 to pawl 18).

The whole of the mechanism according to the invention that is to say, the key lever 5, assembler control lever 16, the operating connections between said levers and a driving wheel for the cam rollers, may be conveniently carried in a frame or casing pivotally supported on the 55

machine frame, for example as shown in Figure 4, at the side of the main keyboard, so that said mechanism may be swung as a whole about a pivot 22 outwardly to an inoperative position, 5 to give access to its parts and to permit outward swinging of the keyboard.

Within the scope of the invention, and as shown in the drawings, one unit may comprise 10 the assemblage in a common frame or casing of two power actuated mechanisms, each a replica of the other, with the pivots and axes of the respective levers concentrically arranged, for mounting between two groups of magazines arranged side by side, so that the assembler entrance of the respective groups of magazines may 15 be independently controlled from the one unit. In such cases, when each magazine group has its own keyboard, the outward swinging of the unit is necessarily preceded by the outward 20 swinging of one of the keyboards, and in order to leave a clear path for the movement of the unit, the invention includes means for swinging also the escapement actuating reeds which usually remain in their normal vertical position when 25 the keyboard is moved out of operative position. One arrangement for carrying out this modification of the invention is shown in Figures 3 and 4. As illustrated, the keyboard adapted to be swung outwardly to permit the swinging movement of 30 the power unit is the auxiliary keyboard 5 which is swung from the solid line position shown in Fig. 4 to the dotted line position shown therein and, when this has been accomplished, the unit itself may be swung from the solid line position 35 to the dotted line position, wherein it will present no interference to the swinging movement of the main keyboard at the left.

Ordinarily, the reeds 24 associated with the auxiliary keyboard are arranged in a fixed frame. 40 In the present machine, however, such a frame would interfere with the swinging movement of the power unit, previously alluded to, and accordingly, the reeds 24 are carried in a frame 25 supported on a horizontal pivot 26 near its 45 upper end. Near the rear of the auxiliary keyboard frame, there is located an upwardly projecting lug 27 (in the form of an L-shaped bracket adjustably mounted by a screw through a slot in one arm thereof) and, as the keyboard 5 is swung outwardly in the manner heretofore described, the lug 27 engages the reed frame 25 at the rear and near the lower end thereof, so as to swing the frame from the position shown in solid lines in Figs. 3 and 4 to the 50 position shown in dotted lines therein and, when the reed frame 25 is so located, it will clear the unit as the latter is swung from one position to another. The degree of clearance provided is clearly indicated in Fig. 4.

60 The construction of the assembler entrance section 28 is illustrated in Figs. 3 and 3^a and is substantially the same as disclosed in the patent to Gayter et al., No. 2,068,288, issued January 19, 1937, to which reference may be had for a more detailed description of the parts. 65 Suffice it to say, when the assembler entrance section is in the position shown in Fig. 3, it completes an operative connection between the lower magazine of a pair in operative position and the 70 fixed lower section 29 of the usual assembler entrance; whereas, when the assembler entrance section 28 is moved to the position shown in Fig. 3^a, it completes an operative connection between the fixed lower section of the assembler entrance and the upper magazine in operative 75

position, this latter connection being through the medium of a relatively fixed section 30 of the assembler entrance and located at the lower end of the upper magazine in operative position.

As previously stated, the operation or pivoting 5 of the assembler entrance section 28 from the position shown in Fig. 3 to the position shown in Fig. 3^a and vice versa is through the power-operated mechanism, previously described, and when the control lever 16 is in the position 10 shown in Fig. 1, wherein the roller 15 is in the high portion of the cam 14, the assembler entrance section is in position to complete the operative connection between the upper magazine in operative position and the fixed lower 15 section 29 of the assembler entrance; whereas, when the roller 15 is at a low portion of the cam, the assembler entrance section is in the position shown in Fig. 3, where it completes the operative connection between the lower magazine 20 in operative position and the section 29 of the assembler entrance.

The section 28 of the assembler entrance is 25 pivotally mounted on a cross shaft 31 arranged at the front of the machine and is actuated from the lever arm 16 through the medium of a link 32 and an arm 33 to which the link is connected at one end and which at the opposite end is fixed to said cross shaft 31.

It must be understood that the invention is 30 not limited solely to the details of the form described above since various modifications may be introduced as they become desirable or necessary in order to carry the invention into effect under different conditions and requirements 35 which have to be fulfilled, without departing from the scope of the invention.

Having described my invention, I declare that what I claim and desire to secure by Letters Patent is:—

40 1. A device for setting an adjustable section of the assembler entrance in a typographical composing machine adapted to be equipped with a pair of superposed matrix magazines and wherein the section is adjustable to two different positions 45 to make and break an operative connection between either one of the magazines and a fixed section of the assembler entrance, said device comprising a power-driven member and a key-controlled member adapted for frictional engagement therewith to actuate a mechanical power transmission system for moving the adjustable section to the desired setting.

2. A device for setting an adjustable section of the assembler entrance in a typographical composing machine adapted to be equipped with a pair of superposed matrix magazines and wherein the section is adjustable to two different positions 55 to make and break an operative connection between either one of the magazines and a fixed section of the assembler entrance, said device comprising a power driven member and a key-controlled element adapted to engage by co-acting V-shaped and V-grooved peripheries, and a mechanical power transmission system driven 60 by said key-controlling member when engaged with said power driven member for moving the adjustable section.

3. A device as claimed in claim 1 comprising an eccentric cam adapted, when released by said key, 70 to fall into frictional engagement with a power driven roller.

4. A device for setting an adjustable section of the assembler entrance in a typographical composing machine, adapted to be equipped with a 75

- pair of superposed matrix magazines and wherein the section is adjustable to two different positions to make and break an operative connection between either one of the magazines and a fixed section of the assembler entrance, said device comprising a power-driven member, a key controlled member adapted for frictional engagement therewith to actuate a mechanical power transmission system for moving the adjustable section to the desired setting, and means for locking the mechanical power transmission system in position after adjustment.
5. A device as claimed in claim 4 wherein said locking means are released by said controlling key upon initiation of a subsequent adjustment.
10. In a typographical composing machine a device as claimed in claim 1 built as a unit, pivotally mounted on the machine frame to allow it to be swung outwards for access.
15. 7. In a typographical composing machine a plurality of devices as claimed in claim 1 built as a single unit pivotally mounted upon the machine frame.
20. 8. In a typographical composing machine embodying a device as claimed in claim 1, means for moving a set of escapement actuating reeds out of the path of the pivotally mounted unit when desired.
25. 9. In a typographical composing machine embodying a device as claimed in claim 1, means for moving a set of escapement actuating reeds out of the path of the pivotally mounted unit when desired, comprising a pivotally mounted frame carrying said reeds and means on a pivoted keyboard whereby the swinging of the keyboard about its pivot effects simultaneous swinging of said frame of reeds.
30. 10. In a typographical composing machine embodying a device as claimed in claim 1 and comprising a main and an auxiliary group of magazines, each with its own keyboard, a pivotally mounted frame carrying the escapement actuating reeds of the auxiliary keyboard, and a projection on the auxiliary keyboard frame adapted, when the auxiliary keyboard is swung about its pivot, to engage with said reed frame, and swing it about its pivot out of the path of said device.
35. 11. In a typographical composing machine adapted to be equipped with a pair of superposed matrix magazines, and an assembler entrance adjustable to permit the assembly of matrices from either magazine, the combination therewith of means for adjusting the assembler entrance including a power-driven device operable during certain alternate predetermined increments of movement to adjust the assembler entrance to cooperate with one magazine and during other alternate predetermined increments of movement with the other magazine, and means including a member adapted upon movement in one direction to operate said device through said predetermined increments, and upon movement in another direction to be restored to normal position.
40. 12. In a typographical composing machine adapted to be equipped with a pair of superposed matrix magazines, and an assembler entrance adjustable to permit the assembly of matrices from either magazine, the combination therewith of means for adjusting the assembler entrance including a power-driven device operable during certain alternate predetermined increments of movement to adjust the assembler entrance to cooperate with one magazine, and during other alternate predetermined increments of movement, and key-controlled
- means including a member adapted upon movement in one direction to operate said device through said predetermined increments, and upon movement in another direction to be restored to normal position.
45. 13. In a typographical composing machine adapted to be equipped with a pair of superposed matrix magazines, and an assembler entrance adjustable to permit the assembly of matrices from either magazine, the combination therewith of means for adjusting the assembler entrance including a power-driven device having an element rotatable in one direction and operable during certain alternate predetermined increments of movement to adjust the assembler entrance to cooperate with one magazine and during other alternate predetermined increments of movement, with the other magazine, and means including a member adapted upon movement in one direction to rotate said element during said predetermined increments of movement and upon movement in another direction to be restored to normal position.
50. 14. In a typographical composing machine adapted to be equipped with a pair of superposed matrix magazines, and an assembler entrance adjustable to permit the assembly of matrices from either magazine, the combination therewith of means for adjusting the assembler entrance including a power-driven cam rotatable in one direction only and intermediate connections between the cam and the assembler entrance, said cam being formed so that upon rotation it will effect the adjustment of the assembler entrance alternately into cooperative relation with the magazines, and means for rotating said cam and including a member adapted upon movement in one direction to rotate the cam to effect said adjustments of the assembler entrance, and upon movement in another direction to be restored to normal position.
55. 15. In a typographical composing machine adapted to be equipped with a pair of superposed matrix magazines, and an assembler entrance adjustable to permit the assembly of matrices from either magazine, the combination therewith of means for adjusting the assembler entrance including a power-driven cam rotatable in one direction only, intermediate connections between the cam and assembler entrance, and means including a ratchet device for rotating the cam through equal increments of movement, said cam being formed so that upon certain alternate increments of movement it will adjust the assembler entrance into cooperative relation with one magazine and during other alternate increments of movement with the other magazine.
60. 16. In a typographical composing machine adapted to be equipped with a plurality of superposed matrix magazines and with mechanism for rendering one or another of the magazines operative without shifting said magazines, the combination with such mechanism of devices including a cam rotatable during certain alternate predetermined increments of movement in one direction to adjust said mechanism for cooperation with one magazine and during other alternate predetermined increments of movement in the same direction to adjust said mechanism for cooperation with another magazine, and a power means for rotating said cam including a member adapted upon movement in one direction to rotate the cam through said increments of movement, and upon movement in another direction to be restored to normal position.

17. A combination according to claim 14, wherein the cam in effecting the adjustment of the assembler entrance is rotated through equal increments of movement, and means for preventing overrunning of the cam.
18. A combination according to claim 14, wherein the cam in effecting the adjustment of the assembler entrance is rotated through equal increments of movement, means for preventing overrunning of the cam, and means for preventing retrograde movement of the cam.
19. A combination according to claim 14, wherein the cam in effecting the adjustment of the assembler entrance is rotated through equal

increments of movement, means including a pawl adapted when operative to prevent advance movement of the cam, and key means for rendering the pawl inoperative.

20. A combination according to claim 14, wherein the cam in effecting the adjustment of the assembler entrance is rotated through equal increments of movement, means including a pawl adapted when operative to prevent advance movement of the cam, and key means for controlling the movement of the cam and for rendering the pawl inoperative.

ARTHUR STANILAND HAYWARD.
